UNITED STATES PATENT OFFICE.

AUGUST A. KLANN, OF WAYNESBORO, VIRGINIA.

COMBINATION MAGNET AND PRIMARY VALVE.

Application filed January 19, 1927. Serial No. 162,129.

This invention relates to improvements in pipe organs, especially in the valve mechanism for controlling the passage of air to the pipes, and it consists in the constructions, 5 combinations and arrangements herein described and claimed.

An object of the invention is to provide a unit in which the primary valve and the electro-magnet for actuating it are so combined that the installation of the unit in the wind chest of an organ at once accomplishes the installation of the essential parts for controlling the flow of air to an organ pipe.

A further object of the invention is to provide a unit of the character described, in which the structure is so simplified that the cost of manufacture has been reduced to a minimum, this, however, without the sacrifice of any essential elements.

Other objects and advantages appear in the following specification, reference being had to the accompanying drawings, in which

Figure 1 is a cross section of an organ wind chest illustrating the installation therein of the improved unitary or combined valve and magnet,

Figure 2 is a detail sectional view of parts in Figure 1,

Figure 3 is a horizontal section taken substantially on the line 3—3 of Figure 2,

Figure 4 is a cross section similar to Figure 1 illustrating a slight modification in the structure of the unit, making use of a pneumatic instead of a puff,

Figure 5 is a cross section of a wind chest illustrating a second modification in which the electro-magnetically actuated valve controls the organ pipe orifice directly.

Figure 6 is a detail cross section on the line 40 6—6 of Fig. 1,

Figure 7 is a detail perspective view of the improved hinge herein employed.

Reference may be had to my co-pending application for Letters Patent for combination magnet and primary valve, filed September 17, 1925, Serial No. 56,982, upon which the present invention is an improvement. An outstanding advantage of the improvement resides in that novel construction by 45 which it is made possible to provide a unitary device which, being complete in itself, makes

it possible to quickly and accurately install the essential air control element of an organ pipe in the wind chest of an organ.

In carrying out the invention, provision is 55 made of a base generally indicated 1 which, being hollow, as shown in Figure 2, provides the receptacle or casing for the primary valve 2. The valve 2 is thus distinguished because its function precedes that of the secondary 60 or organ pipe valve 3. The latter controls the passage of air from the wind chest 4 to the orifice 5 of an organ pipe 6.

Attached to the base 1 by integral or other formation is an exhaust tube 7. This tube 65 has a slight continuation at 8 on the interior of the base providing a seat upon which the primary valve 2 is normally held by the pressure of air within the wind chest and by spring pressure. The upper exposed end of 70 the tube 7 has a flange 9 receiving suitable fastening means 10 by which the unit is attached in part to a center of the wind chest. A bracket 11 completes the mounting of the unit upon said member. The exhaust tube 7 75 communicates with an opening 12 through which air on the inside of the base or casing 1 may exhaust to atmosphere.

A short externally threaded tube 13 serves as the connector between the base 1 and the 80 rigid half 14 of a puff which includes the flexible diaphragm 15 by which the secondary valve 3 is carried. The edge of the diaphragm is clamped upon the rigid half 14 of the puff by means of a ring 16. The 85 bracket 11 is held in position between the base 1 and the rigid half 14 of the puff, it being evident that should the puff become loose upon the base 1 it is only necessary to turn the half 14 in the right direction thereby 90 screwing down tight upon the bracket 11 and upon the base 1. The tube 13 extends sufficiently high within the rigid half 14 to provide a seat or rest for the lower end of a light spring 17, the upper end of this spring 95 presses against the valve 3 and normally holds the valve in place over the orifice 5, thereby cutting off wind chest air from the organ pipe 6.

A cover 18 closes the open side of the base 100 1 and completes the valve casing. The cover is secured to the base by screws 19 or other

wise, the screws passing through an outstanding lug both upon the base and cover. An externally threaded tube 20 which is located on the same axis with the exhaust tube 7 provides a complementary valve seat to the seat 8. The valve tube 20 may be screwed in and out upon the cover 18 to effect adjustment in respect to the primary valve 2, the adjustment of the tube being set by a nut 21.

10 The electro magnet 22 by which the primary valve 2 is actuated, is fastened in place upon the cover 18 of the base 1 by means of a screw 23 which is introduced from the inside of the base or casing as plainly shown in Fig. 2. The screw 23 is headed into the core of the electro magnet as shown. A short piece of metal 24 provides what may be known as a magnet base, this base being interposed between the core of the magnet and cover 18 of the base. The magnet base has a bracket which has pendant ears 25 (Fig. 7) constituting part of a special electric circuit.

15 A combined armature 26 and valve lever 27 is pivoted at 28 between the ears 25, the lever 27 carrying a block 27^a (Fig. 7) fitting between the ears 25 and being provided with ears 25^b for the purpose of receiving the pivot pin 28 as shown. The armature 26 is secured to the lever 27 and extends into proximity with the extremity of the pole of the electromagnet so that energization of the electromagnet will attract the armature and rock it upon its pivot. The lever 27 is apertured at its extremity as at 29 to receive the stem 30 of the primary valve, and at 29^a to receive the fixed rod 29^b carrying a spring 29^c to hold the primary valve seated. The end of the valve stem is threaded to receive a pair of washers 31 between which the lever 27 is situated.

20 Adjustment of the valve stem may be made in respect to the lever by turning the washers up or down.

Fig. 4 illustrates a modification which differs in construction from the form in Figs. 1 and 2 only in that the secondary valve 3 is operated by a pneumatic rather than the diaphragm of a so-called puff, and that the electromagnet 22 is mounted directly upon the cover 18 of the base 1. All parts of a construction similar to that in Figs. 1 and 2 are designated by corresponding reference numerals. The spring 17 which may be regarded as the equivalent of the spring 17 in Fig. 2 is mounted on the outside of the pneumatic where it is readily accessible of being carried by a stem 17^a which in turn has appropriate swivel supports 17^b upon arms 17^c extending from the upper and lower portions of the bellows.

25 The connector tube 13 serves to secure the bottom 32 upon the base 1. The bellows 33 of the pneumatic carries the secondary or organ pipe valve 3 as already stated. The spring 17 normally holds the valve in position against the orifice 5 so that air may not

enter the organ pipe 6 from the wind chest 4.

An extension 34 of the cover 18 provides a place at which the magnet 22 is mounted by means of the screw 23. It is noted that the magnet base 24 (Fig. 2) is now omitted and that the hinge bracket having the pendant ears 25 are attached directly to the base cover.

Electric current to be sent through the magnet 22 by any desired means, the means herein employed consisting of an organ key 35 (Figs. 1 to 5 inclusive) which has associated contacts 36 and 37 connected with wires 38 and 39 leading to the terminals of the magnet. The wire 38 embraces a suitable source of current 40. Depression of the organ key will close an electrical circuit which can be readily traced over the foregoing elements causing energization of the electromagnet and attraction of the armature 26.

Figure 5 illustrates a modification in which the structure has been simplified in order to enable a direct control of air from the wind chest 41 in respect to the orifice 42 of the organ pipe 43 by means of the organ pipe valve 44. The action, it will be observed, is direct, the interposed pneumatic devices in Figs. 1, 2 and 4 being omitted. A base 45 suitably secured at 26 to one of the members of the wind chest serves as a mounting for an electromagnet 47, the electromagnet being secured by means of a screw 48. Ears 49, pendant from the base 45 provide a mounting for the pivot 50 of the combined armature 51 and valve arm 52. The latter carries the organ pipe valve 44 as shown. A stem 53 with an adjustable stop 54 limits the rocking movement of the valve arm. A second stem 55 has an adjustable abutment 56 against which one end of a light spring 57 rests. The other end of the spring bears against the under side of the valve arm and holds the valve in a normally closed position against the orifice 42.

The operation

is readily understood. In Figs. 1 and 4 the internal air pressure of the wind chest 4 pressure of the spring 29^c holds the primary valve 2 seated against the end of the exhaust tube 7, thus leaving the valve tube 20 uncovered and admitting compressed air from the wind chest to the interior of the base or casing 1 whence it enters the puff in Figs. 1 and 2 or the pneumatic in Fig. 4 and holds the secondary or organ pipe valve seated against the orifice 5 so that wind chest air can not reach the organ pipe 6. A depression of the organ key 35 will close the electrical circuit illustrated causing energization of the electromagnet 22 and the attraction of the armature 26. The rocking of the combined armature and valve lever pulls the primary valve 2 down into seating position upon the valve tube 20 so that the interior of the base or casing 1 is placed in communication with the atmosphere through the exhaust tube 7 and

opening 12. The predominating pressure on the inside of the wind chest forces the diaphragm 15 or the bellows 33 down causing unseating of the secondary valve 3 and the 5 opening of the orifice 5 to the interior of the wind chest. Compressed air now reaches the organ pipe 6 so that the latter is caused to speak. Release of the organ key 35 and the energization of the electromagnet causes a 10 reestablishment of the original condition.

It is to be noted that the various adjustments which may be made are essential to the prompt and accurate operation of the device. These adjustments are effected at the 15 washers 31 whereby the relationship of the stem 30 to the valve lever 27 may be altered to suit requirements, and also of the primary valve 2 upon the stem 30.

The foregoing action may be described 20 as being indirect in that it requires the unseating of the primary valve 2 before the secondary valve 3 becomes unseated. But in Fig. 5 the action is direct. Energization of the electromagnet 47 causes an immediate unseating of the organ pipe valve 44 so that air from the wind chest 41 is at once admitted to the orifice 42 and thus to the organ pipe 43. In any case the construction is compact and simple, making it easy to install the device 25 and as easy to take it out for the purpose of replacement or repair.

In order to avoid the entrance of foreign matter to the exhaust port or opening 7, provision is made of a dust cap 58, this consisting merely of a cover slotted crosswise on the 30 under side as at 59.

While the construction and arrangement of the improved combination magnet and valves is that of a generally preferred form, obviously 35 modifications and changes may be made without departing from the spirit of the invention or the scope of the claims.

I claim:—

1. A device of the character described comprising a base and cover secured thereto comprising a casing, an exhaust tube communicating with the casing constituting means by which the device is mounted in a fixed position, a valve tube in the cover communicable 40 with a source of relatively high air pressure, a primary valve in the casing, a spring-seated secondary valve controlling the admission of high pressure air to an organ pipe, a pneumatic device carrying the secondary valve being 45 mounted upon the casing and in communication with the interior thereof, an electro-magnet mounted upon the cover of the base, a combined armature and lever pivotally supported upon the cover, and a connection between the primary valve and lever for moving the primary valve into seating position upon the valve tube and upon the exhaust tube on energization and deenergization of the electromagnet.

2. A device of the character described com-

prising a casing having an exhaust tube having a flange by which the device may be fixedly mounted, a valve tube communicable with the interior of the casing and with a source of relatively high pressure, a primary 70 valve within the casing, a spring-seated secondary valve controlling the admission of high pressure air to an organ pipe, a pneumatic device carrying the secondary valve having means by which it is attached to and has communication with the casing, an electro-magnet, a magnet base and means by which the base and magnet are secured in common upon the casing, said base having ears, a combined armature and valve lever 80 pivoted upon the ears, and a connection between the lever and primary valve.

3. A device of the character described comprising a casing communicable with comparatively high and low pressure of air, a valve 85 effecting a control to establish communication with either source of compressed air, means subject to electrical impulses mounted upon the casing and having means by which said impulses are communicated to the valve to effect the foregoing control, said means including a combined armature associated with the electro magnet and lever associated with the valve, a stem upon the casing over which the lever loosely passes and a spring mounted 90 upon the stem and bearing against the lever normally seating the valve upon the point of communication of one of said sources of air while the electro magnet is deenergized.

4. A device of the character described comprising a casing having a pair of openings communicable with sources of relatively high and low air pressure respectively, a primary valve within the casing, a secondary valve controlling the admission of high pressure 105 air to an organ pipe, a pneumatic device including a bellows carrying the secondary valve and being mounted upon the casing in communication with the interior thereof, an electro magnet mounted upon the casing, a 110 combined armature and lever pivoted upon the casing being respectively associated with the electro magnet and connected with the primary valve, resilient means carried by the casing normally seating the primary valve 115 upon the low air pressure opening, resilient means normally keeping the secondary valve seated upon an organ pipe opening said means including a pair of arms carried by the bellows, a stem swivelly connecting the arms and 120 a spring mounted upon the stem in engagement with the arms.

5. A device of the character described comprising a base, an electro-magnet mounted upon the base, a valve, ears on the base, 125 an arm for the valve and an armature for the magnet assembled in pivotal relationship with the ears, a stem on the base co-acting with the arm, and resilient means carried by the stem engaging the arm.

6. A device of the character described comprising an electro-magnet, a valve that is subject to control by the electro-magnet, a casing containing the valve, a cover for the casing providing a base for the electro-magnet, said cover having an opening in respect to which the valve is movable, an arm connected with

the valve and an armature for the electro-magnet, means by which the combined arm and armature are pivotally mounted upon the cover, and resilient means tending to displace the valve from the opening and retract the armature from the electro-magnet. 10

AUGUST A. KLANN.
